UNITED STATES PATENT OFFICE.

WILLIAM VON DEEST, OF ASHTON, IOWA.

SCAFFOLD.

1,368,668.

Specification of Letters Patent. Patented Feb. 15, 1921.

Application filed September 19, 1919. Serial No. 324,813.

To all whom it may concern:

Be it known that I, WILLIAM VON DEEST, a citizen of the United States, residing at Ashton, in the county of Osceola, State of Iowa, have invented a new and useful Scaffold; and I do hereby declare the following to be a full, clear, and exact description of the invention, such as will enable others skilled in the art to which it appertains to make and use the same.

The invention relates to scaffolds and has for its object to provide a scaffold particularly adapted for mechanics working on a building wall or the like wherein it is necessary to lower or raise the scaffold from time to time. Also to provide a scaffold of this character which is suspended from a roof of a building by blocks and tackles which are secured to roof hooks or the like and to the ends of the scaffold, the lines from the blocks and tackles leading over pulleys on the scaffold to a rotatable drum, thereby providing means for the operator to adjust the scaffold as a whole upwardly or downwardly as desired without going to each end of the scaffold to operate the blocks and tackle.

A further object is to provide a wheeled seat on runways of the scaffold thereby allowing the painter or other mechanic to move the seat longitudinally on the scaffold without getting out of the seat.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a view in elevation showing the scaffold suspended from a roof or the like.

Fig. 2 is a vertical sectional view taken on line 2—2 of Fig. 1.

Fig. 3 is a perspective detail view of a portion of the main board of the scaffold and the adjacent track.

Referring to the drawings, the numeral 1 designates the cornice of a roof and 2 the scaffold suspended against the wall of the building. The scaffold 2 comprises an elongated board 3, the ends of which are pro-

vided with upwardly extending brackets 4, which brackets receive the lower block 5 of blocks and falls 6; the upper blocks 7 of the blocks and falls 6 are hooked into eyes 8 of roof hooks 9, thereby suspending the scaffold from the cornice 1 of a roof. The leads 10 of the blocks and falls pass under pulleys 11 carried by the scaffold and then pass around and are secured to a vertically disposed drum 12, which drum is rotatably mounted in bearings of arms 13 carried by a longitudinally adjustable yoke 14 slidably mounted on the scaffold board 3, said yoke having one of its horizontal portions provided with a set screw 15, whereby the yoke 14 may be securely clamped in any desired position against horizontal movement. The upper end of the shaft of the drum 12, is provided with a crank 16 whereby the drum may be rotated as desired to wind the lines 10 on said drum, there being a ratchet 17 and pawl 17' for holding the drum in any position to which it may have been rotated. However, during a lowering operation the pawl may be thrown out of engagement with the ratchet and the unwinding of the lines 10 from the drum 12 may be controlled by a brake member 18 around which a strap brake 19 extends and has its end secured to one of the arms 13 as at 20, the other end of the strap brake being connected as at 21 to a lever 22 which is pivoted as at 23 to the inner end of the yoke 14. It will be seen that by operating the lever 22 the brake strap 19 may be tensioned around the brake member 18, thereby controlling the rotation of the vertically disposed drum 12 as the scaffold lowers under its own weight and that of the operator.

Longitudinally movable on tracks 24, carried by upstanding brackets 25 which are secured to the scaffold board 3 is a wheeled seat 26, said wheeled seat being provided with a foot rest 27 and shelves 28 for the reception of paint buckets and the like. This seat is adapted to be occupied by the operator as he works, he may easily move the seat longitudinally as desired which is a decided advantage in painting where painters work in courses that is paint a horizontal strip and then lower the scaffold for another course. All that is necessary for the operator to do when he wants to move the seat longitudinally is to grasp the rail 29 and pull the seat to any desired position.

The rod 29 is supported by the brackets 30, which are secured to the outside track 24 as at 31.

From the above it will be seen that a scaffold is provided which may be easily and quickly adjusted upwardly or downwardly and one wherein a longitudinally movable seat is provided for the operator so that he may move from place to place as desired.

10 The invention having been set forth what is claimed as new and useful is:—

A scaffolding comprising a horizontally disposed platform, said platform being suspended from blocks and falls at its ends, 15 the leads from said falls extending downwardly and under horizontally pivoted pulleys carried by the rear side of the platform, said leads extending toward each other and around a vertically pivoted drum, 20 said drum being pivotally mounted between

horizontally disposed arms of a platform receiving yoke, a set screw passing through the upper horizontal member of the yoke for holding said yoke in any position to which it may be moved longitudinally of the platform, a brake carried by the drum shaft and controlled from a lever, said lever being pivotally connected to the forward end of the yoke and means for rotating the vertically disposed drum and means for holding said drum in any position to which it may be moved.

25 In testimony whereof I have signed my name to this specification in the presence of two subscribing witnesses.

WILLIAM VON DEEST.
